DIE SET WITH FEEDING MEANS

August J. England, Providence, R. I.

Application November 19, 1946, Serial No. 710,755

6 Claims. (Cl. 164—88)

1

This invention relates to a die set with feeding means assembled therewith.

In the operation of dies the means cooperating with the dieing thrust for feeding the stock is usually fully automatic. However, the arrangement is such that some manipulation is often required to cooperate the feeding means with the dieing thrust. In instances where a feeding means has been combined with the dies usually no sufficiently positive feed is provided for.

One of the objects of this invention is to provide a feeding means which will be assembled on and operate in response to the relative movement of a pair of dies and which will be positive in its action.

Another object of this invention is to provide a positive feed which will engage a part of the work for moving the same forward while a stop is provided to limit the amount that the work is fed forward.

Another object of this invention is to provide for the release of the stop means when the feeding device operates.

Another object of this invention is to provide all of these parts in a rather simple construction.

Another object of this invention is to provide all of these parts in a single unit which may be assembled on the machine at one time.

With these and other objects in view, the invention consists of certain novel features of construction, as will be more fully described and particularly pointed out in the appended claims.

In the accompanying drawings:

Fig. 1 is a side elevation of a die set with my feeding means in combination therewith;

Fig. 2 is a sectional view on line 2—2 of Fig. 1 looking downwardly on the lower die;

Fig. 3 is a sectional view on line 3—3 of Fig. 2;

Fig. 4 is a sectional view on the staggered line 4—4 of Fig. 2;

Fig. 5 is a sectional view on line 5—5 of Fig. 2;

Fig. 6 is a sectional view similar to Fig. 4 but taken parallel thereto in a position to show the relative positions of the feed fingers and stop finger;

Fig. 7 is a sectional view on line 7—7 of Fig. 2;

Fig. 8 is a perspective view illustrating diagrammatically the engagement of the two fingers with the work;

Fig. 9 is an elevation similar to Fig. 1 showing the modified form of device;

Fig. 10 is an end view of the structure shown in Fig. 9;

Fig. 11 is a perspective view of the carriage which mounts the feed dog in the modification of Figs. 9 and 10;

Fig. 12 is a fragmental elevation showing a still further modification of carriage for the feed dog and modified actuating abutment.

In proceeding with this invention, I mount

2

upon the lower die block certain feeding means such as a feeding finger and a stop finger, the feeding finger being arranged for reciprocating movement which will be actuated by some abutment or means which is carried by the upper die and be engaged as the dies relatively move.

With reference to the drawings: 9 designates generally a die of the follow type wherein the upper die block carries a piercing tool P, a forcer 10 or shaping plunger or tool F and a blanking plunger B. The lower die block carries the dies associated therewith which have the cavities or openings CP, CF, and CB. The tools and dies are arranged in tandem fashion so that after the first operation the stock is fed to the next point and a second operation performed and the work-piece cut from the stock by the blanking plunger B, all in a manner well known to workers familiar with die sets of this general character. It is here

pointed out that the above is merely an exemplary procedure and is significant only as to the last step wherein an area of the stock is removed, leaving an opening by the operation of the blanking plunger CB. The machine on which the die set is attached is designated 10 and the lower die block 11 has mounted thereon a cutter plate 12 upon which there are stock guides 13, 13', and a stripper plate 14. The stock is fed between the guides 13, 13' as at 15 (see Fig. 7) and is held

20 in position between these guides by a shoe 16 pivotally mounted as at 17 in a lever 18 which is pivoted as at 19 and drawn downwardly by spring 20 engaging the reduced end portion thereof. The pivot 19 of this lever is supported 25 on the post 22 which extends from the die block 11 and which is held in position by the screw 23.

Spaced from the cutter plate 12 (see Figs. 5 and 7) are members 27 which are spaced from each other and provide guides for guiding the 30 movement of a carriage 26 in a linear path at the edge of the cutter plate 12. Each guide 27 is in the form of an L-shaped block which provides a portion 28 to extend over the upper edge of the carriage 26. Screws 31, 32 serve to hold 35 these parts 27 in position. The carriage is provided with a roll 33 at one end and a spring 34 engages a pin 35 on the carriage and a pin 36 on a member 27 to draw the carriage in one direction to the left as shown in Figs. 1 and 2.

40 The upper die block 40 (see Fig. 1) is guided by means of posts 42 extending upwardly from the lower die and sockets 43 in the upper die as the same is reciprocated from some plunger which is not shown. This upper die block carries 45 an abutment or cam 44 to engage the roll 33 and move the carriage 26 against the action of the spring 34.

The carriage 26 has an L-shaped block 45 mounted upon it (see Fig. 3) by means of a slot 50 46 through the block and a screw 47 passing

through this slot and into the carriage 26. A tongue 48 and groove 49 in cooperation with the slot and screw serve for adjustment of this block 45 relative to the carriage. This block carries a yoke 50 by reason of the slot 51 for the reception of the overhanging portion 52 of the block that the yoke may be adjustably held on the block by set screw 53 (see Fig. 2) extending through the yoke and engaging the block. A groove or recess 56 (see Fig. 3) receives the feed finger 57 which is pivotally mounted therein on a pin 54 secured by set screw 55 in the yoke. In order to urge this feed finger downwardly spring 58 (see Fig. 2) is mounted by means of screw 59 on the yoke to engage the edge of this feed finger and urge it downwardly. The feed finger has at one end thereof a hook 60 which is so shaped as to engage a cut out portion or opening left in the stock when the work-piece has been blanked therefrom so that movement of the slide when this hook is engaged with the opening O will move the stock forward.

On a portion which is fixed relative to the die block 11 such for instance as the block 61, I pivotally mount a stop finger 62 which is offset as shown in Fig. 2 so as to be properly positioned with reference to the work. This finger is pivotally mounted at 63 (Fig. 4) and is urged downwardly by a leaf spring 64 mounted at 65 on the block 61. This stop finger has a downwardly projecting portion 66 which will also engage in the opening O in the work and positively limit the forward movement of the work as shown in Fig. 8, in which the openings are illustrative of the opening left in the stock after blanking out the work-piece. This stop finger 62 is shaped on its under surface 67 so as to ride along the pivot pin 54 and be lifted from the work as the carriage moves rearwardly to take another bite for feeding the work forward. Thus the stop finger is lifted from position for a portion of the stroke of the carriage depending on the under shape of the stop finger and whereby when the carriage in feeding returns to a certain position the stop finger will drop into position and limit the movement of the work forward. Block 61 is held in position by bolt 70 passing through it into the die block 11.

In some cases it is desirable to provide a carriage for the feed finger 57 which will rock instead of slide relative to the lower die block and I have shown in Figs. 9, 10 and 11 a feed finger 57' which is mounted in a carriage 75 (see Fig. 11) which is pivotally mounted by means of ears 76. This carriage also has a roll 77 which will be engaged by the cam surface or abutment 44 to rock it about its pivotal openings 78 in the ears 76 which are mounted on the pivot pin 79. The mounting block for the feeding finger 57' is shown at 80 on the carriage which pivotally mounts the finger 57' on pin 81, the finger being swung downwardly by means of spring 82 supported on rod 83 and engaging the finger as at 84. In this manner a reciprocating motion is given to the feed finger 57' by means of the rocking carriage while the pivot pin 81 serves in a similar manner to raise and lower the stop finger which will be the same as heretofore indicated. A spring 85 will serve to return the carriage and cause it to follow the cam as it is raised and lowered.

In some cases instead of having a cam surface such as 44 I may provide a carriage of the shape shown in Fig. 12 at 86. In this case there is a

downwardly extending portion or arm 87 providing a pivot 88 for the feed finger 57', the feed finger being swung about the pivot 88 by means of spring 89 engaging the feed finger as at 90 and engaging an arm 91 of the carriage. This carriage has an arm 92 which extends outwardly in a position to be engaged by an abutment 93 carried by the upper die in an adjustable manner as at 94 so as to engage this arm and rock the carriage to reciprocate the feed finger 57'.

It will thus appear that various means may be provided for reciprocating the feed finger but that a pivot for the feed finger may in all cases serve to actuate the stop finger that the proper actuation thereof may be had.

I claim:

1. The combination with a die set having one die movable toward the other, a work feed comprising means responsive to the movement of said dies toward each other to engage the work and feed the same forwardly, stop means to engage the work and limit the forward movement of the work, said feeding means carrying a portion to engage and render inactive the stop means during a portion of the movement of said feeding means.

2. The combination with a die set having one die movable toward the other, a work feed comprising means on one die to engage the work and feed the same forwardly, a cam on the other die to actuate said means upon movement of said dies toward each other, stop means to engage the work and limit the forward movement of the work, said feeding means carrying a portion to engage and render inactive the stop means during a portion of the movement of said feeding means.

3. In combination with a die set having one die movable toward the other, a work feed comprising a feed finger to engage an opening in the work, a carriage pivotally mounting said finger, means responsive to the movement of the die set for moving said carriage to reciprocate said finger to feed the work, a stop finger movably mounted on said die to engage an opening in the work and limit the forward movement thereof and means on said carriage to lift said stop finger during a portion of the movement of the carriage.

4. The combination set forth in claim 3 wherein said means for lifting the stop finger comprises a pin pivotally mounting the feed finger.

5. The combination set forth in claim 3 wherein said means responsive to the movement of said dies comprises an abutment on one die to engage and move said carriage.

6. The combination set forth in claim 3 wherein said means responsive to the movement of said dies comprises a cam on one die to engage and move said carriage.

AUGUST J. ENGLAND.
